FIG.1

FIG.2

FIG.3

FIG.4

FIG. 1 is a perspective view of a can or the like showing my new design;

FIG. 2 is an enlarged fragmentary top perspective view;

FIG. 3 is a fragmentary elevational view thereof; and

FIG. 4 is a top view thereof.

The characteristic feature of this design resides in the combination of the vertical wall closure neck shown with a flat top container having the general height to width proportions shown.

I claim:

The ornamental design for a can or the like, substantially as shown and described.
